US00D951994S

(12) **United States Design Patent** (10) Patent No.: **US D951,994 S**
(45) Date of Patent: **** May 17, 2022**

(54) **DISPLAY SCREEN OR PORTION THEREOF WITH GRAPHICAL USER INTERFACE**

(71) Applicant: **Mitsubishi Electric Corporation**, Tokyo (JP)

(72) Inventors: **Akiko Imaishi**, Tokyo (JP); **Shinsaku Fukutaka**, Tokyo (JP); **Munetaka Nishihira**, Tokyo (JP); **Tsuyoshi Sempuku**, Tokyo (JP); **Shuhei Suzuki**, Tokyo (JP); **Misato Yuasa**, Tokyo (JP)

(73) Assignee: **Mitsubishi Electric Corporation**, Tokyo (JP)

(**) Term: **15 Years**

(21) Appl. No.: **29/753,774**

(22) Filed: **Oct. 1, 2020**

(30) **Foreign Application Priority Data**

Apr. 1, 2020 (JP) ..... 2020-006399 D

(51) **LOC (13) Cl.** **14-04**

(57) **CLAIM**

The ornamental design for a display screen or portion thereof with graphical user interface, as shown and described.

DESCRIPTION

FIG. 1 is a front view of a display screen or portion thereof with graphical user interface showing our new design; and, FIG. 2 is a second embodiment thereof.

The broken lines showing a display screen or portion thereof form no part of the claimed design. The remaining broken lines showing portions of the graphical user interface form no part of the claimed design.

1 Claim, 2 Drawing Sheets
